(57) **CLAIM**

The ornamental design for a smoking debris collection device, as shown and described above.

DESCRIPTION

FIG. 1 is a perspective view showing of the smoking debris collection device, showing our new design;

FIG. 2 is front view thereof, the opposite side being a mirror image;

FIG. 3 is a side view thereof, the opposite side being a mirror image;

FIG. 4 is top view thereof;

FIG. 5 is perspective view of a first alternate embodiment of the smoking debris collection device, showing our new design

FIG. 6 is front view thereof, the opposite side being a mirror image;

FIG. 7 is side view thereof, the opposite side being a mirror image; and,

FIG. 8 is a top view thereof.
